CLAIM

We claim the ornamental design for a colander scoop, as shown and described.

DESCRIPTION

FIG. 1 is a perspective view of the colander scoop of the present invention.

FIG. 2 is a left elevation of the colander scoop of the present invention.

FIG. 3 is a right elevation of the colander scoop of the present invention.

FIG. 4 is a top plan view of the colander scoop of the present invention.

FIG. 5 is a bottom plan view of the colander scoop of the present invention.

FIG. 6 is a rear elevation of the colander scoop of the present invention; and,

FIG. 7 is a front elevation of the colander scoop of the present invention.

The broken lines in the drawings represent unclaimed features.
